UNITED STATES PATENT OFFICE.

CHARLES C. ALLEN, OF KANSAS CITY, MISSOURI.

LIQUID-MEASURER.

939,198.

Specification of Letters Patent.

Patented Nov. 9, 1909.

Application filed December 8, 1908. Serial No. 466,544.

To all whom it may concern:

Be it known that I, CHARLES C. ALLEN, a citizen of the United States of America, residing at Kansas City, in the county of Jackson and State of Missouri, have invented certain new and useful Improvements in Liquid-Measurers; and I do hereby declare that the following is a full, clear, and exact description of the invention, such as will enable others to make and use the same, reference being had to the accompanying drawings, forming a part of this specification.

The invention relates particularly to measures for discharging from a body of the liquid of equal minute quantities.

The object of the invention is to displace the exact quantity, step by step, and with great facility, and without the quantities varying.

The invention consists in the novel construction and combination of parts, such as will be first fully described and then specifically pointed out in the claims.

Figure 1. is a side view, in elevation, of the liquid measuring instrument. Fig. 2. is a vertical, sectional view of the same. Fig. 3. is a detail, side view of the liquid holding tube and sleeve, with the upper end broken away, to show the stopper or diaphragm. Fig. 4. is a top view of the instrument with the plunger being broken away. Fig. 5. is a detail isometric view of the sleeve on the liquid holding tube, enlarged.

Similar numerals of reference indicate corresponding parts in all the figures of the drawing.

Referring to the drawings, 7 indicates a liquid-holding receptacle which is in the form of a tube, and for the purpose of containing acids and other liquids is preferably made of glass. Upon the upper end of the tube is a close-fitting sleeve 8, which is short in length and secured to the tube by suitable adhesive substances, such as cement.

Upon the outer surface of the sleeve and near the lower end thereof, is an outwardly extended annular flange 9, formed integral with the sleeve. Upon the lower end of the tube is an inwardly extended portion 10, forming the bottom of the tube, and upon the outer surface of said portion is a short projection 11, the surface of which is gradually reduced or tapered nearly to a point. Through said bottom portion 10 of the tube and the projection 11 extends a small capillary discharge opening 12. In the upper

end of the tube 7 is a close-fitting, movable diaphragm or stopper 13, which is made of suitable material, such as cork.

The tube 7 is filled with the liquid and 60 the stopper inserted in the upper end of the tube to a position in which the outer surface of the stopper is upon a line with said upper portion of the tube.

The means for advancing the stopper and 65 discharging a measured quantity of the liquid consists of a hollow member or casing 14, of the proper length and thickness and upon the outer surface of the casing at an intermediate point relative to the ends 70 of the casing is an annular enlargement 17, for the hand of the operator. In the lower portion 16, of the casing, is an opening 18, of the requisite size to admit of the entrance of the upper end of the sleeve 8, above the 75 flange 9, the upper surface of which flange comes into contact with the lower end portion 16, of the casing. In the upper portion of the casing is an opening 19, the size of which is the same as the inner circumference of the tube 7. Upon the outer surface of the lower end portion 16, of the casing, is a screw-thread portion 19^x, extending downwardly from the line of the lower surface of the enlargement 17, of the casing a 85 short distance. To this screw-thread portion of the casing is fitted a collar 20, upon the inner surface and upper end portion of which collar is a screw-threaded portion 21, which is turned upon the threads 18, of the 90 sleeve, the lower, inner portion of the collar fitting the lower smooth portion of the sleeve. The outer surface of collar is milled. The lower end of the collar 20 extends downwardly a short distance below the line of 95 the lower end of the sleeve 16, and also a short distance below the lower portion of flange 9, in the sleeve 8, and is bent inwardly at 22, and in close contact with the lower portion of said sleeve 8, leaving between said 100 portion 22 of the collar and the lower surface of the flange, an annular space 23, within which is a rubber ring or gasket 24.

At the upper end of the portion 15, of the casing 14, is a flat end portion or cap 105 25, closing said end. In the said end or cap is a small opening 26, concentric with the opening 19, of the said portion of the casing. From the opening 26 extend in opposite directions radial openings 27, which 110 are short in length.

28 indicates a pressure-imparting rod to

the stopper 13, in the tube 7. The lower end portion 28^x, of the rod which forms the plunger is nearly of the same size as the inner circumference of the opening 19, in the upper portion 15, of the casing 14, and is approximately two-thirds the length of said portion of the casing. The upper end portion of the rod is reduced in size, and is nearly of the circumference of the opening 10 26, in the cap 25, of the casing 14. This rod is made of considerable length sufficient to extend within the tube 7, to the lower end thereof, and is provided with a removable cap 29, secured to the rod by a screw 29^x.

15 Upon the rod 28, are secured a number of lugs or pins 30, arranged at equal distances apart and in vertical series, the lugs upon one side of the rod alternating in position with the lugs upon the other portion or side 20 of the rod transverse thereto, the lugs in the same vertical plane being opposite the other. The lugs are made to pass readily through the radial openings 27, in the cap 25, when the rod is adjusted in position by a partial 25 rotary movement communicated to the rod.

The distance between the lower surface of one lug in one vertical series of the lugs and the lower surface of the adjacent lug in the other vertical series constitutes a measure 30 of the liquid to be discharged in a specific quantity and the lugs are therefore placed on the rod with the determinate distances accurately computed.

In the employment of the instrument for 35 the purposes premised, the lower end portion 28^x, of the rod 28, as seen in Fig. 2, bears upon the upper surface of the stopper 13. Rotation is first imparted to the rod 28 sufficient to cause two of the lugs 30, 30, 40 upon opposite sides of the rod, to come in position above the radial openings 27, 27, in the cap 25, and pressure being imparted to the rod the lugs pass within radial openings advancing the stopper 13, until the lugs 30, 45 transverse thereto come into contact with the cap 26, thus directing the movement of the rod. The stopper 13 in its pressure downwardly upon the liquid expels a small 50 quantity of the liquid through the capillary discharge opening 12, and upon a rotary movement imparted to the rod 28 to bring one pair of the lugs 30 over the openings 27, operating to repeat the movement and an 55 equal quantity of the liquid is discharged through the capillary discharge opening 12, in the lower end of the tube, equal to the measure pre-determined by the distance between the lower surfaces of the lugs in the transverse, vertical planes of rod 28, and 60 step by step. In this manner the liquid is discharged with facility with no variance in the quantity.

It is customary to fill a number of the tubes with the liquid and affix the sleeve 65 thereto, and after use the tubes may be dis-

carded. The lugs 30, which are shown round, may be varied in form, as preferred.

Having fully described my invention, what I now claim as new and desire to secure by Letters Patent is:

1. In liquid measurers the combination with a receptacle or container of liquids having a capillary discharge opening, a movable diaphragm adapted to displace said liquid in small quantities, a casing, connecting means connecting said casing with said receptacle, and a plunger within said casing coacting with the diaphragm to move said diaphragm within the receptacle, and measuring devices on the plunger for determining the amount of liquid displaced by the movement of the diaphragm.

2. In liquid measurers, the combination with a tube for holding the liquid having an opening in its upper end, and a capillary discharge opening, a movable diaphragm adapted to displace the liquid in small quantities, a casing having an opening in its lower end registering with the opening in the upper end of said tube, means connecting said tube with said casing, and a plunger within said casing, a plunger rod and measuring devices on the said rod adapted to co-act with and control the movement of said plunger.

3. In liquid measurers the combination with a tube for holding the liquid having an opening in its upper end and a capillary discharge opening, a movable diaphragm within said tube adapted to displace the liquid in small quantities, a casing having an opening in its lower end registering with the opening in the upper end of said tube, said casing having an opening in its upper end, a plunger within said casing, co-acting with the diaphragm, and a plunger rod, and measuring devices on the plunger rod, controlling the movement of the plunger.

4. In liquid measurers the combination with a tube for holding the liquid having an opening in its upper end, and a capillary discharge opening, a movable diaphragm within said tube adapted to displace the liquid in small quantities, a casing having an opening in its lower end registering with the opening in the upper end of said tube and an opening in the upper end of said casing having radial openings extending therefrom, means connecting said tube with said casing, and a plunger within the said casing, a plunger-rod movable in the opening in the upper end of said casing, and lugs on said rod arranged at measured distances and adapted to move with said rod through said radial openings.

5. In liquid measurers the combination with a tube for holding the liquid having an opening in its upper end, and a capillary discharge opening, a movable diaphragm within said tube adapted to displace the li-

uid in small quantities, a casing having an opening registering with the opening in the upper end of said tube, said casing having an opening in the upper end of said casing, and radial openings extending therefrom in opposite directions, a plunger within said casing adapted to co-act with the diaphragm in said tube, and a rod within said opening in the upper end of said casing con-

nected with said plunger, and lugs on said rod in vertical series, and the lugs in one series alternating in position with the lugs in the other series and spaced at measured distances apart.

CHARLES C. ALLEN.
